Primary Examiner — Kevin Rudzinski*Assistant Examiner* — John Reickel(74) *Attorney, Agent, or Firm* — K&L Gates LLP**CLAIM**

The ornamental design for display screen portion having a graphical user interface for patient monitoring, as shown and described.

DESCRIPTION

FIG. 1 is a front view of a display screen portion having a graphical user interface for patient monitoring, showing the new design as it would appear on a mobile device; and, FIG. 2 is a front view of a display screen portion having a graphical user interface for patient monitoring, showing the new design as it would appear on a desktop device. No claim is made to the dashed lines, dashed image, or text. Said dashed lines, dashed image, and text being presented only for the environmental purposes.
